(57) CLAIM

The ornamental design for a wearable finger ring, as shown and described.

DESCRIPTION

FIG. 1 is a perspective view of a wearable finger ring; FIG. 2 is a front view of the wearable finger ring of FIG. 1. FIG. 3 is a back view of the wearable finger ring of FIG. 1. FIG. 4 is a left view of the wearable finger ring of FIG. 1. FIG. 5 is a right view of the wearable finger ring of FIG. 1. FIG. 6 is a top view of the wearable finger ring of FIG. 1; and, FIG. 7 is a bottom view of the wearable finger ring of FIG. 1.

The broken lines shown in the drawings represent portions of the wearable finger ring that form no part of the claimed design.

1 Claim, 5 Drawing Sheets
